UNITED STATES PATENT OFFICE

JOHN HENRY BURNS, JR., OF TAMPA, FLORIDA

ROCKING HORSE

Application filed June 28, 1929. Serial No. 374,367.

The primary object of this invention is to make a practical rocking horse that can be sent through mails, and to this end, to provide a knockdown structure which when separated into its constituent parts may be put into a carton within the mailing dimension limits.

Another object of the invention is to provide a stout, rigid, and durable construction capable of being easily put together and taken apart without the use of tools.

A further object is to produce a rocking horse suited for use by small children, upon which they may readily seat themselves without help, and from which they will not be likely to fall.

The standard types of rocking horses and rocking seats intended for children are usually very expensive and heavy, and are assembled at a factory with no provision for being collapsed or knocked down for shipment. They must be sent by freight or express, since they are much too bulky to be sent by parcels post which has dimensional limits too small for such articles. In several types of such seats or toys, the child when small cannot climb into or upon the place where it is to sit but must be lifted up by some one else.

In the description of the preferred embodiment of this invention chosen as a typical construction for purposes of illustration, it will be seen that the invention accomplishes its objects in a simple, inexpensive, and efficient manner, and it will be evident to those skilled in the art that many changes may be made in the details of construction and arrangement of parts without departing from the spirit of the invention as set forth in the claims and without sacrificing any of its advantages.

In the accompanying drawings, Figure 1 is a side elevation of the device; Fig. 2 a rear end elevation; Fig. 3 a plan view; and Fig. 4 a perspective view.

A platform 1 has metallic cross bars 2, 2, secured upon its under surface, the bars having their ends bent to form brackets which are perforated to receive bolts 3, 3, which pass through perforations in side pieces or rockers 4, 4, the perforations being so located that the top of the platform is flush with the straight upper edges of the rockers. The straight side edge of the platform abutting against the edge of the rockers and held firmly in place by the bolts gives a very rigid construction, further strengthened by a cross bar 5 bolted at each end to the lower margin of the rockers, this cross bar 5 being substantially identical with the bars 2.

A seat 6 is supported by four stout legs 7 which are preferably round bars having tenons at their ends to seat within mortises in the seat and in the platform. A head 8 cut and decorated to represent a horse's head is secured by lag bolts and nuts 9, 9, upon the front portion of the upper surface of the seat 6. A handle consisting of a round bar 10 passes through the head where it may be readily grasped by a child seated astride of the seat 6 with its feet resting upon the platform 1. Additional rigidity may be secured by using a tension rod or bolt 11 set close to the rear of where the head rests upon the seat; the rod passing through perforations in the seat and in the platform.

By the use of wing nuts 12 upon the various bolts, the purchaser may assemble the device for use without needing any tools, and after the assembled device has been in use, if one needs to transport it for any considerable distance, the removal of these nuts allows the structure to be taken apart.

Even a small child will find but little difficulty in stepping upon the platform at a height of five or six inches, and standing there, the seat is at a height to be mounted without trouble, since the feet of the child rest upon the platform when he is astride of the seat. Grasping the handle, the child can

rock freely and safely backward and forward, the center of gravity lying well below the center of curvature of the rockers. At each end, the rockers are provided with a 5 down-turned tip portion 13 to engage the floor to limit the rocking movement. If the child rocks with sufficient force to strike the tips before the momentum is overcome by the lifting action of the rockers, the device 10 will tend to slide if the surface upon which it rests is smooth, and this sliding movement is a further source of amusement to the child.

The broad platform, rigidly bracing the 15 rockers and forming a firm footing for the child while rocking and when getting on and off the seat, also acts as a secure support for the legs carrying the seat. The tension rod 11 will not be needed when the rocker is used 20 by small children but its presence will add to the certainty that the structure will not fail with even the largest riders. A most important feature is the handle 10 within 25 easy grasp of the rider, adding to his confidence and assuring his safety in a way that cannot be accomplished by the usual cord or leather bridle.

In the salesroom, one or two of the devices, 30 assembled for demonstration, require little space, while the stock packed in cartons, ready for immediate delivery, is in the most convenient form, especially in view of the possibility of sending the cartons by parcels post. It will of course be evident that the 35 embodiment is to be considered as illustrative and not restrictive, the claims indicating the scope of the invention.

I claim:

1. A collapsible or knockdown rocking 40 horse adapted for being packed within mailing limits, comprising a flat platform, mortised to receive legs, flat rockers, detachable means for securing the rockers to the platform, a flat seat mortised to receive legs, legs 45 adapted for detachable seating within the mortises in the seat and in the platform, and a flat head having detachable means for securing it to the seat.

2. A structure as in claim 1, in which the 50 head is perforated to receive a handle and having a handle consisting of a bar adapted to extend through the perforation in the head.

3. A rocking device comprising two rockers 55 having straight upper edges, a platform detachably secured between the rockers with its upper surface substantially flush with the upper edges of the rockers, legs mounted in the platform, a seat supported by the legs, 60 tension means holding the seat, legs, and platform detachably together, a head secured to the seat, and a handle comprising a rod passing through the head and projecting on each side to be grasped by a rider on the seat.

4. A rocking device comprising a plat-

form, a rocker at each edge of the platform, metallic cross bars secured to the under side of the platform and detachably secured to the rockers, legs detachably mounted upon the platform, a seat detachably mounted upon the legs, and tension means securing the seat, legs, and platform together.

5. A structure as in claim 4, having a handle connected with the seat and detachable therefrom.

In testimony of which I hereunto affix my signature.
